A. Randolph, Jr. Attorney

UNITED STATES PATENT OFFICE.

RUSSELL O. DINGER, OF MELVINA, WISCONSIN.

SPARK-PLUG.

1,325,439.

Specification of Letters Patent. Patented Dec. 16, 1919.

Application filed May 4, 1918. Serial No. 232,550.

To all whom it may concern:

Be it known that I, RUSSELL O. DINGER, a citizen of the United States, residing at Melvina, in the county of Monroe and State 5 of Wisconsin, have invented certain new and useful Improvements in Spark-Plugs; and I do hereby declare the following to be a full, clear, and exact description of the invention, such as will enable others skilled 10 in the art to which it appertains to make and use the same.

This invention relates to improvements in spark plugs and has for one of its objects the provision of a device of this character whereby a comparatively large circular spark will be produced between the electrodes of the spark plug, thereby rendering an efficient spark for the fuel of the engine.

Another object of this invention is the provision of a circular electrode surrounding the central electrode of the plug in spaced relation so as to cause a comparatively large circular spark and also will not be affected by oil and carbon forming 25 upon the circular electrode.

A still further object of this invention is the provision of a spark plug of the above stated character, which shall be simple, durable and efficient, and which may be manufactured and sold at a comparatively low cost.

With these and other objects in view as will become more apparent as the description proceeds, the invention consists in certain 35 novel features of construction, combination, and arrangement of parts as will be hereinafter more fully described and claimed.

For a complete understanding of my invention, reference is to be had to the following description and accompanying drawing, in which:—

Figure 1 is a side elevation partly in section of a spark plug constructed in accordance with my invention,

Fig. 2 is an end view of the same,

Fig. 3 is a fragmentary vertical sectional view illustrating the electrodes, and

Fig. 4 is a fragmentary sectional view of 50 the circular electrode.

Referring in detail to the drawing, the numeral 1 indicates a body of a spark plug having the usual threaded portion 2 for threaded engagement with the opening in 55 the cylinder of an engine. The body 1 has

mounted therein the insulator 3 carrying the central electrode 4, the insulator 3 being secured in the body 1 by the lock nut 5. The central electrode 4 depends downwardly through the extension 2 in spaced relation thereto. The extension 2 has secured thereto a plurality of downwardly and inwardly directed arms 6 which have their inner ends formed upon a ring 7 constructed of platinum or other material suitable for the purpose. The ring 7 forms an electrode of circular formation which is disposed about the lower end of the central electrode 4 in spaced relation thereto so that the spark jumping from the central electrode to the ring 7 will be in a circular path giving a comparatively large spark. The inner face of the ring 7 is flat as illustrated at 8, and the spark is adapted to play upon the flat surface and oil thrown by the pistons of the engine will be caught by the round face of the ring 7 and prevented from coming in contact with the flat face 8 on which the spark plays. By having the ring constructed in this manner it provides a comparatively dry and clean 80 surface for the spark to work upon at all times.

While I have shown and described the preferred embodiment of my invention, it will be understood that minor changes in 85 construction, combination, and arrangement of parts may be made without departing from the spirit and scope of the invention as claimed.

Having thus described my invention what 90 I claim is:

A spark plug including a body and an insulator having a central electrode that has one end projecting beyond the inner end of said body and centrally thereof, a plurality of relatively spaced curved arms having one of their ends formed on the inner end of said body, and their other ends spaced from the end of the electrode, and a ring having a curved outer face formed on the last named ends of the arms and having a flat inner face disposed about the end of the electrode and in spaced relation thereto.

In testimony whereof I affix my signature in presence of two witnesses.

RUSSELL O. DINGER.

Witnesses:

HERMAN LEIS,
JOHN C. MEYERS.
